PRINTING DEVICES

John P. Sebring, Lewiston, N.Y., assignor to Moore Business Forms, Inc., Niagara Falls, N.Y., a corporation of Delaware

Filed Feb. 4, 1966, Ser. No. 525,074
8 Claims. (Cl. 101—93)

This invention relates to printing devices and more particularly to such devices wherein the impression on the sheet is made by causing a hammer to strike the reverse side of the paper or other medium and force the immediate area of the front surface thereof against a type face.

This particular printing device probably finds its most important use in computer machines, where a print-out is made on a continuous multiple part form. In many of these machines the imprinting is made against a type chain carrying a complete font of type. Such a chain is moved to and fro selectively so that the proper character is placed into printing position, and then the impression is made by the print hammer striking through the multiple part form from the rear surface thereof.

However, it has been found, particularly in the case of the last few carbon impressions in a multiple form, that a shadow or halo appears around the impressed figure or number. This phenomenon is caused by the action of the hammer which appears to mold at least the rearward layers of the multiple form around the edges of the hammer, due to the partial embedment of the hammer element in the multiple relatively soft or yielding form pack. Usually the halo or shadow appears only on the last few elements of the multiple form but obviously this constitutes a disadvantage and drawback in this kind of printing.

It is therefore a principal object of the present invention to provide means for use in printing apparatus of the class described for eliminating such undesirable shadow or halo impressions.

The present invention results from the discovery that such defects can be eliminated by the interposition of a particular kind of shield between the print hammer and the back of the form. This shield is of laminar form and is made of multiple layers of thin plastic material and the invention contemplates the provision broadly of a range of layers of the material and thicknesses within which the desired result becomes appreciable, and also the provision of optimum laminar and thickness qualifications for the maximum results.

More specifically, the invention contemplates the provision of a laminar shield or pack comprised of multiple layers of Mylar plastic. Mylar is a trademark distinguishing a polyester film material manufactured by E. I. du Pont de Nemours & Co., the material being polyethylene terephthalate, which is a polymer formed by the condensation reaction of ethylene glycol and terephthalic acid. This material will be further defined by its known properties in the present specification.

The invention thus embraces an impact printing machine of the kind described employing this novel and improved shield, and also includes the multiple layer shield as an article of manufacture.

Other objects and features of novelty will be apparent from the following specification when read in connection with the accompanying drawings in which one embodiment of the invention is illustrated by way of example.

In the drawings:

FIGURES 1 and 2 are diagrammatic views, not drawn to scale, showing respectively prior art arrangements with the parts in position prior to and during impact by the hammer;

2

FIGURES 3 and 4 are views similar to FIGURES 1 and 2 respectively and illustrative of the two corresponding stages with the use of the novel shield forming an essential element of the present invention;

5 FIGURE 5 is a fragmentary view suggesting one way of securing the novel shield to the nose frame of a printing apparatus and in front of the hammers;

FIGURE 6 is an enlarged fragmentary view showing the preferred structure of the plastic shield;

10 FIGURE 7 is a fragmentary view illustrating as well as possible, considering the limitations of drawing, the undesirable halos or shadows which prevail in the impact printing machines now in use; and

15 FIGURE 8 is a similar view illustrating the freedom from shadow or halo on a record sheet nearest the hammer in a device following the principles of the present invention.

20 In the generic and quite diagrammatic showings in FIGURES 1 and 2, the prior art developments along this line of printing are exemplified. At 10 in these figures there is indicated a type element representative of numerous prior art constructions, whether carried upon a rotatable cylinder or arranged in the form of a chain. The character comprising letters, numbers, or punctuation marks is of course embossed or otherwise delineated upon the face of the type member 10 as at 12.

25 Similarly illustrated in diagrammatic fashion is a ribbon 15 which can be moved step-by-step across the face 12 of the type 10 by suitable actuation of the reels 16 and 30 upon which the ribbon is wound.

30 A projectable hammer member 20 of which there may be any desired number selectively actuated, is mounted for delivering an impact against the rear surface of the sheet or manifold pack which passes between the hammer 35 and the type and ribbon set-up. Such a manifold pack is illustrated, for example, at 25 in these figures of drawing and will be seen to comprise in the illustrated example, four record sheets *a* and three interposed carbon or transfer sheets *b*.

40 Thus as used in the claims, the term "sheet of record material" or the like shall mean a single layer or a multi-layer pack.

45 Now in the normal operation of currently used devices of this character, as illustrated in FIGURES 1 and 2, the hammer 20 in delivering its blow strikes the rear surface of the pack 25 and forces it against the portion of the ribbon 15 which overlies the type face 12 of the type element 10. As shown in possibly somewhat exaggerated form due to the necessary enlargement of the

50 thickness of the pack for illustrative purposes, the face 21 of the hammer compresses the sheets *a* and *b* and embeds itself slightly within the rear surface of the pack causing the rearmost sheets to "wrap-around" the margins of the hammer face 21 and thus cause the carbon or transfer coating to frame the character impression with a rough irregularly imprinted shadow or halo. This undesirable framing of the character is suggested in FIGURE 7 of the drawings and it occurs definitely on the rearmost record sheet *a* and frequently on several of the rearward sheets.

60 As mentioned in the presentation of the objects of the present invention, applicant has provided a buffer strip which is interposed between the face 21 of the hammer 20 and the rearmost record sheet *a* of the pack 25. This guard strip or shield is diagrammatically illustrated at 30 in FIGURES 3 and 4 of the drawings. The idle position of the various parts is suggested in FIGURE 3 and the positions shown in FIGURE 4 are diagrammatically 65 illustrative of the effect upon impact of the hammer upon the rear face of the guard or shield 30 which lies against the manifold pack 25.

The impact of the hammer is absorbed by the shield strip 30 and seems to broaden out the force of impact of the hammer so that the rearward portions of the multiple form do not mold themselves around the hammer face, but the hammer still transmits enough pressure to make a good impression, such as suggested in FIGURE 8 of the drawings.

Experimentation has shown that this novel and beneficial effect is limited to some extent by the thickness of the individual sheets comprising the guard strip, the number of sheets employed, and the plastic material of which the sheets are made.

Before going into these somewhat critical data, it would be well to show an example of one installation of the guard sheet in relation to the hammers. In FIGURE 6 of the drawings a typical pack or laminar shield is illustrated in somewhat diagrammatic exaggerated form. The pack comprises outer sheets A and B and inner sheets C which are embraced between the outer sheets. In order to provide a convenient envelope for holding the laminations together, the end sheets A and B are somewhat wider than the intermediate sheets C and the protruding edges D may be secured together adhesively or otherwise, for example, by means of a strip of double-face adhesive tape suggested at D'.

In FIGURE 5 there is illustrated one form of hammer enclosure, sometimes referred to as a "nose cone." This casing is indicated at 50 and comprises a front face 51, a top panel 52, end wall 53, and attaching flange 54. Along the width of the enclosure 50 is provided an elongated slot 60 through which a multiplicity of hammers 20 are adapted to be projected.

The laminar shield or buffer pack 30 may be secured across the face 51 of the frame 50 as indicated in FIGURE 5, the flange portion D of the pack being secured to the member 50 in any suitable fashion as suggested at 55.

It has been determined by experimentation that the desired result is attained by the use of multiple sheets of polyester plastic material made from polyethylene terephthalate, the polymer formed by the condensation reaction of ethylene glycol and terephthalic acid. This material is manufactured by E. I. du Pont de Nemours & Co. under the trademark Mylar. Identifying properties of the preferred form of Mylar for use in this application may be enumerated as follows: ultimate tensile strength—40,000 p.s.i.; stress to produce 5% elongation—21,000 to 25,000 p.s.i.; ultimate elongation—50%; tensile modulus—800,000 p.s.i.; impact strength—6.0 kg.-cm./mil; density—1.37 grams/cc.; coefficient of friction (kinetic) (film-to-film) 0.38; melting point, 250° to 265° C.

With regard to the thickness of the individual laminations and the number of laminations employed, it is interesting to note the following results of experiments:

Summarizing these results, the following delineations appear. The described improvement begins to make itself appreciable in the case of each material, with two layers of film each of a thickness of 0.0035 inch—total thickness 0.007 inch; two layers of film each of a thickness of .005 inch—total thickness 0.010 inch, and six layers of film each of a thickness of .0015 inch—total thickness 0.090 inch. It can be said then that with respect to all laminar thicknesses any total of over 0.011 inch or a total of below 0.007 inch, gives poor results. Also, it has been determined that individual single sheets of more than 0.005 inch of thickness are not usable.

Finally, the optimum results superior to any other combinations have been found to be the use of seven laminations of film of 0.0015 inch of thickness, giving a total thickness of 0.0105 inch.

Thus it may be stated that the effective total thickness lies within the approximate range of 0.007 inch to 0.0105 inch.

It is understood that the present invention is applicable to a wide variety of impact hammer printing devices and that the machines illustrated and described diagrammatically herein are for generic illustration only. Also, various changes and modifications may be made in the embodiments disclosed without departing from the scope of the invention as determined by the subjoined claims.

Having thus described the invention, what is claimed as new and desired to be secured by Letters Patent is:

1. Printing apparatus comprising a type member having a surface formed to present a type character, means for supporting a sheet of record material with its surface to be printed presented in front of said type surface, hammer means for delivering a blow to the rear surface of said record material to force the front face against said type surface to imprint a character thereon, laminar means supported in front of said hammer and between the hammer and the rear surface of said record sheet to sustain the direct force of the hammer blow and eliminate the production of a halo or shadow image bordering the character reproduced on the record sheet, said laminar means comprising multiple layers of thin plastic sheeting, said plastic sheeting being a polyester film made from polyethylene terephthalate, the polymer formed by the condensation reaction of ethylene glycol and terephthalic acid.

2. The apparatus as set forth in claim 1 in which the film has the following further properties: ultimate tensile strength—40,000 p.s.i.; stress to produce 5% elongation—21,000 to 25,000 p.s.i.; ultimate elongation—50%; tensile modulus—800,000 p.s.i.; density—1.377; and coefficient of friction (kinetic) (film-to-film)—0.38.

3. The apparatus as set forth in claim 1 in which the laminar means comprises a pack of from two to seven

Number of Laminations	Total Thickness	No Change	Slight Improvement	Considerable Improvement	Maximum Results
Lamination thickness, .0015:					
1-----	.0015	x-----	-----	-----	
2-----	.0030	x-----	-----	-----	
3-----	.0045	x-----	-----	-----	
4-----	.0060	x-----	-----	-----	
5-----	.0075	x-----	-----	-----	
6-----	.0090	-----	-----	x-----

3-----	.015	x-----	-----	-----	

layers of film of from 0.0015 inch to 0.005 inch of thickness of each layer.

4. The apparatus as set forth in claim 1 in which the laminar means has a total thickness of from about 0.0070 inch to about 0.0105 inch.

5. The apparatus as set forth in claim 1 in which the total thickness of the laminar means is approximately 0.0105 inch.

6. The apparatus as set forth in claim 1 in which the laminar means comprises seven layers of film each layer about 0.0015 inch thick.

7. Printing apparatus comprising a type member having a surface formed to present a type character, means for supporting a sheet of record material with its surface to be printed presented in front of said type surface, hammer means for delivering a blow to the rear surface of said record material to force the front face against said type surface to imprint a character thereon, laminar means supported in front of said hammer and between the hammer and the rear surface of said record sheet to sustain the direct force of the hammer blow and eliminate the production of a halo or shadow image bordering the character reproduced on the record sheet, said laminar means comprising multiple layers of thin plastic sheeting, said laminar means comprising at least three layers, the inner and outer layers being somewhat wider than the intervening layers and the extended portions of said

inner and outer layers being secured together thus providing an envelope for said intervening layers.

8. As an article of manufacture for use in an impact printing device wherein hammers are employed to strike the rear face of record sheeting to force the forward face thereof against fixed type for effecting an impression, a buffer strip for insertion between said hammers and the record sheeting, said buffer strip comprising from about three to about seven layers of polyester film made from polyethylene terephthalate, the polymer formed by the condensation reaction of ethylene glycol and terephthalic acid, the innermost and outermost layers being somewhat wider than the intervening layers and the extended portions of said inner and outer layers being secured together thus forming an envelope for containing said intervening layers.
